ELECTRICAL BALL GAME APPARATUS

James M. Hobbs, West Durham, N. C.

Application July 22, 1949, Serial No. 196,152

9 Claims. (Cl. 273—120)

1

This invention relates to a novel game apparatus particularly adapted for use at carnivals and similar places of amusement for providing a game of chance and wherein the random movement of a ball on a game board will determine the winning player or players.

More particularly, it is an object of the present invention to provide a game apparatus including electrically energized illuminating means including a plurality of light bulbs each connected in circuit with a plurality of switches and which switches are adapted to be actuated by the random or chance movement of a ball over a game board for indicating a winning number.

A further and particularly important object of the present invention is to provide an illuminated game apparatus wherein the random or chance movement of the ball will cause different illuminating means indicating different winning numbers to be momentarily energized for producing flashing lights and wherein illuminating means for illuminating one number only of the game will be eventually maintained in an energized position by the ball as it reaches a final resting place and which is governed by chance.

Still a further object of the invention is to provide a game apparatus of the aforescribed character of relatively simple construction which is capable of being readily assembled or disassembled and which can be readily stored or transported when in a disassembled condition.

Numerous other objects and advantages of the invention will hereinafter become more fully apparent from the following description of the drawings, illustrating a presently preferred form of the invention, and wherein:

Figure 1 is a top plan view of the assembled game apparatus in its entirety;

Figure 2 is an end elevational view thereof looking from the bottom toward the top of Figure 1;

Figure 3 is an enlarged cross sectional view, partly in elevation taken substantially along a plane as indicated by the line 3—3 of Figure 1;

Figure 4 is an enlarged fragmentary view of a portion of the structure illustrated in Figure 3;

Figure 5 is an enlarged horizontal sectional view taken substantially along a plane as indicated by the line 5—5 of Figure 2 illustrating the electric circuits, illuminating means and switches diagrammatically;

Figure 6 is a vertical sectional view, partly in side elevation on an enlarged scale, taken substantially along a plane as indicated by the line 6—6 of Figure 1;

Figure 7 is a perspective view of the outer sec-

2

Figure 8 is a similar view of the inner section thereof;

Figure 9 is an enlarged fragmentary perspective view, partly in section showing a portion of an end or side of the inner section;

Figure 10 is an exploded perspective view of portions of two parts of the outer section or unit;

Figure 11 is a fragmentary side elevational view of a part of the outer section showing one of the supporting legs thereof in an extended position;

Figure 12 is a view similar to Figure 11 but showing the supporting leg in a folded position;

Figure 13 is an enlarged vertical sectional view taken substantially along a plane as indicated by the line 13—13 of Figure 1, and

Figure 14 is a vertical sectional view taken at a right angle to Figure 13 and substantially along a plane as indicated by the line 14—14 of Figure 13.

20 Referring more specifically to the drawings, the novel game apparatus in its entirety is designated generally 15 and includes an outer unit, designated generally 16 and which constitutes the support for the illuminating means herein-

25 after to be described, and an inner unit, designated generally 17 and which constitutes primarily a support for a plurality of electric switches for controlling the energizing and de-energizing of the illuminating means of the outer unit 16.

30 Said outer unit 16 includes four sections designated generally 18, 19, 20 and 21. Each of said sections comprises an elongated box-like structure having corresponding beveled ends 22. Said beveled ends 22 of each of the sections are provided with complementary barrel portions 23 and 24 which project therefrom and which complementary barrel portions 23 and 24 are adapted to align for receiving retaining pins 25 when

35 adjacent beveled ends 22 of adjacent sections of said outer unit 16 are in abutting engagement, for detachably retaining the outer unit sections assembled, as illustrated in Figures 1 and 7. Each of said sections of the outer unit 16 is provided with a supporting leg 26 which is pivotally connected to a bracket 27 which depends from the underside thereof and which leg is provided with a conventional type of brace 28, formed of pivotally connected sections for holding the leg

40 26 in an extended position, as illustrating in Figure 11, or for permitting the leg 26 to fold against the underside of the section of the outer unit 16 on which it is mounted, as illustrated in Figure 12.

45 50 55 The sections 18, 19 and 20 of said outer unit 16 are identical and each includes a top wall 29

forming a counter and which is provided with six longitudinally spaced openings 39 in each of which is secured two panes of glass 31 having a strip of colored translucent paper or the like 32 interposed therebetween and which bears a numeral. As illustrated in Figure 1, the numerals of the openings 29 of each section 18, 19 and 20 extending from right to left thereof, facing inwardly from the outer side of the outer unit 16, read consecutively "1," "2," "3," "4," "5" and "6." Furthermore the colored translucent strips 32 containing said numerals or on which the numerals are superimposed are each distinctively colored and with the correspondingly numbered openings of the different sections containing strips of the same colors. Beneath each of the openings 39 and within said box-like section 18, 19 or 20 is mounted an electric socket 33 containing a light bulb 34. The sockets and light bulbs 33 and 34 are preferably separated from one another by partitions 35 which separate the interior of the sections 18, 19 and 20 into a plurality of compartments so that light rays from any one bulb 34 can only be emitted through the opening 30 located directly thereabove or through an opening 36 located in the inner wall 37 of said section and which is in transverse alignment with said bulb 34. Each opening 36 preferably includes a diamond-shaped lens 38 which is preferably mounted in a lens frame 39 which is secured in the opening 36 and said lenses 38, if desired, may be of the same color as the strip 32 of the complementary opening 30.

The other section 21 is of the same shape as the sections 18, 19 and 20 but contains no illuminating means or associated parts. Said section 21, adjacent one end thereof, is provided with a hingedly mounted portion or closure 40 which is hinged along the upper edge of one end thereof as seen at 41 so that the closure 40 may be swung upwardly to an open position to afford an opening through the section 21 through which operators may enter or leave the enclosure formed by the outer unit 16. The outer wall of the section 21 is preferably provided with one or more hinged doors or closures 42, as seen in Figure 2, so that the box-like interior of said section 21 may be utilized to store supplies such as lamp bulbs to replace the bulbs 34.

From the foregoing and from a consideration of Figures 1, 5 and 7, it will be readily apparent that said outer unit 16 affords a square enclosure providing a square open space therewithin in which the inner unit or game board section 17 is disposed, as seen in Figures 1 and 5.

The inner switch supporting and game board unit 17 is adapted to be disposed within the outer unit or frame 16 and is sufficiently smaller than said outer unit to afford ample space between the sides and ends of the inner unit 17 and the inner side walls 37 of the sections of the outer unit so that operators of the game apparatus may conveniently move about in such space in operating the game, as will hereinafter be described. Said inner unit 17 includes a top surface or game board 43 to which is secured depending side and end walls 44. The unit 17 also includes a bottom 45 which is hinged as seen at 46 in Figure 6 along one edge thereof to the bottom edge of one of the side walls 44 and which is retained in a closed position, substantially parallel to the top surface 43, by suitable spring latches 47 which are secured to and depend from the opposite side wall 44, as seen in Figure 8. The bottom 45 is provided with pivotally mounted

legs 48, mounted in the same manner as the legs 26 and which are likewise held releasably in extended positions by braces 49, corresponding to the braces 28, so that when the legs 48 are extended, the top surface 43 will be disposed in substantially the same plane as the top surface 29 of the outer frame unit 16.

Said top surface 43 is provided at each corner thereof with an upstanding post 50 and with two additional laterally spaced posts 50 at one of its ends. A fence formed of resilient strands 51 is stretched around the top surface 43 and supported by the posts 50 to entirely fence in said top surface except for an opening between the laterally spaced posts at one end of the surface 43 and which space is provided to receive a chute 52, the discharge end of which extends into said opening and with the other, higher end of which is supported by depending legs 53 which are secured to and rise from the top surface of the section 21 of the outer unit 16. The elastic strands 51 may be formed of rubber or may constitute contractile coiled springs.

The top surface or game board 43 is relatively thick, as illustrated in Figures 13 and 14, and is provided with a plurality of spaced concave recesses 54 in its upper side. A switch box 55 is mounted on the underside of the surface 43 beneath each recess 54 and each switch box 55 has a block 56 secured thereto by fastenings 57. A fastening 58 extends upwardly through each block 56 and into the underside of the surface 43 for supporting the switch boxes 55 on the underside of said surface 43, as best seen in Figure 14. Each recess 54 communicates at its center with a bore 59 which extends downwardly therefrom through the surface 43 and which registers with an opening 60 in the top wall of the switch box 55 disposed therebeneath for reciprocably receiving a rod 61 which extends upwardly from the switch box 55 through the opening 60 and bore 59 and into the recess 54. The rod 61 supports a bridge 62 of electrical conducting material at its lower end, the ends of which bridge are disposed over spaced electrical contacts 63 and 64 which are secured in the bottom of the switch box 55. A contractile coiled spring 65 is fastened to the bridge 62 and to the top of the switch box 55 for urging the bridge 62 and rod 61 upwardly to their positions of Figures 13 and 14 so that the upper end of the rod 61 will extend into the recess 54 and so that the bridge 62 will be above and spaced from the stationary contacts 63 and 64. As previously stated, each of the plurality of recesses 54 of the game board 43 is provided with a switch box 55 and the parts associated therewith as illustrated in Figures 13 and 14.

Referring to Figure 5, the switch boxes 55 are illustrated diagrammatically therein and it will be noted that the number of said switch boxes and accordingly the number of recesses 54 is greater than the number of lamp sockets 33 and lamp bulbs 34. Likewise, each of the switch boxes bear one of the numbers "1," "2," "3," "4," "5" and "6"; however, the number of switch boxes bearing each of the numerals varies as there are a greater number of switch boxes bearing the numeral "1" than the other numerals and the number of switch boxes bearing the different numerals preferably diminish from the numeral "1" to "6" in consecutive order. As best seen in Figures 5 and 9, each side wall and end wall is provided with an inwardly recessed wall portion 66 partially defining a recess 67 of the

unit 17 and which is normally closed by a hinged door 68, provided with a spring latch 69 for retaining it in a closed position, which extends between aligned portions of the side or end wall 44, with which it is associated. The bottom 45 is provided with openings 70 one of which opens into each of the recesses 67. The end wall 44, located beneath the chute 52 supports an electric plug 71 which is disposed in its recess 67 and which is adapted to be attached to a conventional outlet socket, not shown, of an electric extension cord 71a which extends upwardly through the opening 70 of said recess 67 and into which the plug 71 may be engaged upon opening the door 68. Each of the walls 66 of the other recesses 67 mount a master electric socket 72 having six prong receiving slots for receiving a master electric plug 73, as best seen in Figure 9, having six prongs for engaging with the six slots of the plug 72 for making six electrical contacts therewith. The plug 73 which extends into each of said three last mentioned recesses 67 is connected to one end of a multi-wire electric cord 74 that extends upwardly through the opening 70 of said recess 67 so that the plug can be readily plugged into the socket 66 thereof or removed therefrom when the door 68 of said recess is opened, as illustrated in Figure 9. The six wires of each electric cord 74 are connected at their opposite ends to the six contacts of a master electric contact 75 of the outer unit section 18, 19 or 20, which is located adjacent to the side or end wall 44 from which the electric cord 74 extends and each of the six strands of each cord 74 connects with one of the six contacts of the master contact 75, from each of which contacts extends an electrical conductor 76, which conductors pass through apertures in the partitions 35, as seen at 77 in Figure 5. Each of the conductors 76 connects with one of the posts 78 of the sockets 33 of the sections 18, 19 and 20.

A conductor wire 79 extends from one side of the plug 71 around a portion of the unit 17 and outwardly of the recess 67 thereof which is located adjacent the outer unit section 18 and thence into said section 18 adjacent its master contact 75. As seen in Figure 9, said recess 67 contains a contact post 80 to which the wire portion 79 which extends between the unit 17 and the section 18 can be detachably connected. The conductor wire 79 extends through each compartment of the section 18 and connects with each of the sockets 33 thereof by contact with their other posts 81 and then passes through openings 82 in the beveled surfaces 22 into the section 19 where it is provided with a plate 83 so that sections of the conductor 79 which are disposed in the counter sections 18 and 19 may be detached when the sections of the outer unit 16 are disconnected for storage or transportation. The conductor wire 79 similarly connects with posts 81 of each socket 33 of the sections 19 and 20 and is detachably connected at a point adjacent the sections 19 and 20 by another contact plate 83. The lens frames 39 are readily removable from the openings 36 to afford access to the lamp bulbs 34 and sockets 33 and for attaching and detaching sections of the conductor wire 79 to and from the plates 83. Likewise, as seen in Figure 5, the conductor 74 which extends from the recess 67 of the opposite side wall 44 connects with the master contact plate 75 of the section 20 which has wires 76 leading therefrom and one of which connects with each of the posts 78 of the sockets 33 thereof. Similarly, a con-

ductor 74 leading from the end recess 67, located adjacent the section 19, connects with the master contact 75 of said section 19 which likewise has conductors 76 leading therefrom and one of which is connected to each of the contacts 78 of the sockets 33 thereof.

Another conductor 84 leading from the plug 71 connects with the contact post 64 of each of the switches 55, as seen in Figure 5. One of the switches 55, designated by the numeral "1," has three conductors 85 leading from its contact 63, each of which conductors connects with a corresponding contact 86 of each of the three sockets 72 and which contacts 86 connect with the strands of the multi-wire conductors 74 which in turn connect with the contacts of the master contacts 75 which are connected to the sockets 33 numbered "1." Each of the other switches 55 numbered "1" has a conductor 85 leading from its contact 63 and which connects with the contact 63 which has the three conductors 85 leading therefrom so that when any one of the switches 55, numbered "1" is closed, each of the three lamp bulbs 34, designated "1" will be energized. One switch of each of the groups of switches 55 numbered "2," "3," "4," "5," and "6" likewise has three conductors 85 leading therefrom to the proper contact 86 of each of the three sockets 72 for making contact with each of the sockets and bulbs numbered "2," "3," "4," "5" and "6," respectively, and is connected to each of the other correspondingly numbered switches by a conductor 85 leading from the contact 63 of said switch 55, having the three conductors 85, to the contacts 63 of the other switches bearing the same number.

Assuming that the electric circuits, previously described, are connected to a source of electric current, not shown, by the extension cord 71a, all of the switches 55 will normally be maintained in an open position by their springs 65 so that none of the lamp bulbs 34 will be energized. The game board apparatus 15, as previously stated, is primarily adapted to be used at carnivals and similar places of amusement and the players in playing for prizes select a number "1," "2," "3," "4," "5" or "6" and place a coin or marker on or adjacent the opening 30 bearing such number on any one of the three sections 18, 19 or 20. A ball A is then rolled down the chute 52 onto the game board surface 43 and will roll at random about said surface, striking the elastic fence strands 51 which will cause the ball to rebound back and forth in various directions on the board or surface 43. As the ball rolls around the surface 43 it will roll into different recesses 54 and each time that it rolls into a recess 54 the plunger rod 61 which projects into said recess will be depressed for closing the switch 55, associated with said recess for thereby energizing the circuit to the three lamp sockets 33 and lamp bulbs 34 bearing the same number as the switch which is thus closed. However, due to the dished or concave shape of the recesses 54, said ball A, due to its momentum will initially roll into and out of the recesses so that it will engage and disengage a plurality of the recesses 54 and in so doing will cause the differently numbered lamp bulbs 34 to be energized and de-energized producing a flashing light through the openings 30 and 36, which being differently colored, will produce a very attractive and interesting effect. As the ball loses its momentum it will finally come to rest in one of the

recesses 54 for closing the switch 55 thereof and so that each of the lamp bulbs 34, bearing the same numeral as said switch will be maintained energized to indicate the winning number. As there are fewer switches bearing the numeral "6" than the numeral "5" and fewer switches bearing the numeral "5" than the numeral "4" and so on consecutively from "6" to "1" a player winning on the numeral "6" will receive a larger return or a better prize than a player winning on the numeral "5" and so on consecutively from "6" to "1".

Obviously, the number of switches 55 and recesses 54 on the game board surface 43 may be varied and the number of switches bearing each of said numerals may likewise be varied. The entire game apparatus 15 may be made in various sizes. The inner unit 17 is preferably approximately three by five feet in width and length, respectively, and the outer unit 16, as previously stated, is sufficiently larger so that the operators of the game apparatus may readily walk in the spaces afforded between the inner and outer units.

Various modifications and changes are contemplated and may obviously be resorted to, without departing from the spirit or scope of the invention as hereinafter defined by the appended claims.

I claim as my invention:

1. A game apparatus comprising an outer counter unit formed of detachably connected sections defining an endless frame, hinged supporting legs connected to said counter sections for supporting said counter unit in an elevated position, certain of said counter sections having a plurality of separate illuminating means contained therein, said counter sections having openings in the walls thereof provided with distinctively colored lenses for emitting the light rays from the individual illuminating means of said sections, each of the counter sections, provided with the illuminating means, including a corresponding number of correspondingly arranged, distinctively marked illuminating means and lens covered openings, the distinctively marked illuminating means and lens covered openings of each of said counter sections corresponding to those of each of the other counter sections, an electric circuit for each of the distinctively marked illuminating means, said circuits all being adapted to be connected to a source of electric current each circuit connecting the correspondingly marked illuminating means of the counter sections containing illuminating means; an inner game board unit disposed within the opening defined by said counter unit comprising an elongated box-like structure having a relatively thick top wall constituting a game board, hinged legs for supporting said game board unit with its top surface at substantially the level of the top surface of said counter unit, said top surface or game board being provided with a plurality of spaced dished-shaped recesses therein, a normally open switch mounted beneath each recess and including a reciprocating plunger extending into the recess, spring means for normally holding each plunger in raised position for normally maintaining the switches in open or circuit interrupting positions, each of the circuits of the correspondingly marked illuminating means of said counter sections being connected to a plurality of said switches, said game board surface being adapted to support a rolling ball movable into and out of engagement with said recesses for depressing the switch plungers for

energizing and de-energizing the illuminating means connected thereto and in one of which recesses the ball is adapted to lodge for maintaining correspondingly marked illuminating means of said counter sections energized until the ball is removed from said last mentioned recess.

2. A game apparatus as in claim 1, said game board having a resilient fence extending substantially therearound and adapted to cause said ball to rebound therefrom back and forth at random over said game board surface until its momentum is spent.

3. A game apparatus as in claim 1, said game board having a resilient fence extending substantially therearound and adapted to cause said ball to rebound therefrom back and forth at random over said game board surface until its momentum is spent, and a chute supported on another section of the counter unit extending downwardly and inwardly with respect thereto and having a lower discharge end opening over said game board surface, down which the ball is adapted to be rolled for directing and propelling it onto the game board surface.

4. A game apparatus as in claim 1, another section of the counter unit having a hinged closure forming a gate adapted to be opened to provide an entrance opening to or exit from the space defined by said counter unit.

5. A game apparatus as in claim 1, said inner game board unit being substantially smaller than the opening defined by the counter unit to afford a space therebetween for accommodating operators of the game apparatus.

6. A game apparatus as in claim 1, said game board unit having master sockets in a plurality of the sides thereof, each of said master sockets having a plurality of contacts each forming a part of one of said circuits, each of the counter sections provided with the illuminating means having an extension cord provided with a plurality of conductors extending therefrom, each of said conductors being connected to one of the illuminating means, said extension cord being provided at its free end with a multi-pronged plug for engaging one of said master sockets and including a prong to engage each contact of the master socket for detachably connecting each of the switches to one of the illuminating means of said counter section, each of said conductors constituting a part of one of the circuits.

7. A game apparatus as in claim 1, said game board unit having master sockets in a plurality of the sides thereof, each of said master sockets having a plurality of contacts each forming a part of one of said circuits, each of the counter sections provided with the illuminating means having an extension cord provided with a plurality of conductors extending therefrom, each of said conductors being connected to one of the illuminating means, said extension cord being provided at its free end with a multi-pronged plug for engaging one of said master sockets and including a prong to engage each contact of the master socket for detachably connecting each of the switches to one of the illuminating means of said counter section, each of said conductors constituting a part of one of the circuits, said game board unit including depending side and end walls each provided with a recessed portion, said sockets opening into certain of said recessed portions and being supported thereby, closures in said side and end walls for normally closing said recessed portions and for affording access thereto, and said game board unit having a bottom

provided with openings communicating with each of said recessed portions and through which said extension cords and plugs are passable for insertion and removal.

8. A game apparatus as in claim 1, said game board unit having master sockets in a plurality of the sides thereof, each of said master sockets having a plurality of contacts each forming a part of one of said circuits, each of the counter sections provided with the illuminating means having an extension cord provided with a plurality of conductors extending therefrom, each of said conductors being connected to one of the illuminating means, said extension cord being provided at its free end with a multi-pronged plug for engaging one of said master sockets and including a prong to engage each contact of the master socket for detachably connecting each of the switches to one of the illuminating means of said counter section, each of said conductors constituting a part of one of the circuits, said game board unit including depending side and end walls each provided with a recessed portion, said sockets opening into certain of said recessed portions and being supported thereby, closures in said side and end walls for normally closing said recessed portions and for affording access thereto, and said game board unit having a bottom provided with openings communicating with each of said recessed portions and through which said

5

10

extension cords and plugs are passable for insertion and removal, and another of said recesses having a plug supported therein constituting a part of each of said circuits and adapted to be connected to an extension cord leading from a source of electric current and having conductors connected to each of the switches and each of said illuminating means.

15

9. A game apparatus as in claim 1, said game board unit including side and end walls, each of said switches being supported on the underside of the game board surface, said game board unit including a hinged bottom connected to one of said side walls and mounted for downward swinging movement to an open position, the legs of said game board unit being mounted on said bottom, and latch means for normally retaining said bottom in a closed position substantially parallel to the game board surface.
